(57) **CLAIM**

The ornamental design for a bird feeder, as shown and described.

DESCRIPTION

FIG. 1 is a front, right, top perspective view of a bird feeder, showing our new design;

FIG. 2 is a rear, left, bottom perspective view thereof;

FIG. 3 is a front, right, bottom perspective view of its reduced scale in another angle;

FIG. 4 is a front elevational view of the enlarged scale thereof;

FIG. 5 is a rear elevational view of the enlarged scale thereof;

FIG. 6 is a left side view of the enlarged scale thereof;

FIG. 7 is a right side view of the enlarged scale thereof;

FIG. 8 is a top plan view of the enlarged scale thereof;

FIG. 9 is a bottom plan view of the enlarged scale thereof;

FIG. 10 is an enlarged view of detail 10 in FIG. 1;

FIG. 11 is an enlarged view of detail 11 in FIG. 1;

FIG. 12 is an enlarged view of detail 12 in FIG. 1;

FIG. 13 is an enlarged view of detail 13 in FIG. 2;

FIG. 14 is an enlarged view of detail 14 in FIG. 2;

FIG. 15 is an enlarged view of detail 15 in FIG. 3;

FIG. 16 is an enlarged view of detail 16 in FIG. 3;

FIG. 17 is an enlarged view of detail 17 in FIG. 4; and,

FIG. 18 is an enlarged view of detail 18 in FIG. 9.

The dashed broken lines in the figures are for the purposes of illustrating portions of the bird feeder and form no part of the claimed design.

The short-short-long dashed broken lines immediately adjacent to the claimed areas in the views represent the boundaries of the design and form no part of the claimed design. The dash-dot-dash broken lines are for notating enlarged views and form no part of the claimed design.
